UNITED STATES PATENT OFFICE.

GEO. WRIGHT, OF NEW ENGLAND VILLAGE, MASSACHUSETTS.

SELF-ACTING MULE FOR SPINNING.

Specification of Letters Patent No. 11,279, dated July 11, 1854.

To all whom it may concern:

Be it known that I, GEORGE WRIGHT, of New England Village, in the county of Worcester and State of Massachusetts, have 5 invented certain new and useful Improvements in Self-Actor Mules for Spinning; and I hereby declare the following to be a full, clear, and exact description of the same, reference being had to the accompanying 10 drawings, making part of this specification, in which—

Figure 1, is a plan with the carriage taking out; Fig. 2, a side view; Fig. 3, an end view of the hand stock; Fig. 4, a view 15 of the other end of the mule; Figs. 5, 6 and 7, details which will be hereafter referred to.

The nature of my invention consists in transmitting the power which actuates the mule in its and out motions through cone 20 pulleys, in combination with some means of automatically shifting the band upon the cones, by which means a great saving of machinery is effected and I am enabled to give to the carriage a varying velocity, suited 25 to the requirements of the different parts of its traverse.

My invention furthermore consists in backing off the yarn at the moment the spindles are stripped by means of a friction 30 clutch and stationary band which are brought into action by the rising of the stripping wire and operated by the last motion of the carriage as it takes out.

My invention also consists in winding on 35 the yarn as the carriage takes in by means of the aforesaid clutch and cord which clutch is regulated in its bite by the tension of the yarns, so that when the strain upon the latter becomes too great the under faller 40 wires is depressed, thereby opening the clutch and permitting the cord which drives the spindles to slip and thus regulating the degree of tightness with which the yarn is wound.

45 To enable others skilled in the art to make and use my invention, I will proceed to describe its construction and operation.

A is the head stock, B the floor.

C is the main driving pulley upon the 50 shaft D from which motion is communicated through the band E to the operating parts of the machine.

F is a pulley made fast to the shaft G upon which also revolves the loose pulley H. 55 Upon the same shaft is secured the ratchet wheel a with which the pawl b pivoted to

the pulley is kept in contact by the spring c. When the band E is upon the drum F the shaft G is driven in the direction indicated by the arrow in Fig. 2, and the loose pulley H remains stationary. When the band is shifted upon the pulley H the pawl b engages with the ratchet wheel a and the shaft G is driven in the same direction, so that the shaft G is driven constantly and uninterruptedly in one and the same direction whenever the machine is in operation and whether the driving band be upon one or the other of the pulleys F and H. Upon the shaft G is also secured the cone I, the 60 corresponding cone K, being secured to the shaft L which runs in boxes in the end of the carriage ways M, or in other suitable bearings upon the head stock.

The shaft L carries at its extremities 75 pinions d which engage with cog wheels N upon short shafts e projecting from the ways M or otherwise suitably secured to the head stock.

O are drums secured to the cog-wheels N 80 and having pins f upon their peripheries. These drums carry the endless chains or bands P, which take the carriage in and out. These bands pass over carrying rollers Q, which run upon studs projecting from 85 the carriage ways M.

R are arms pivoted to the carriage at g' and secured to the endless band P at h, by which means, as the endless band revolves the carriage will be taken in and out. 90

The speed of the carriage is to be so varied that it shall move out with a velocity suited to the proper performance of the spinning operation, take in at a much more rapid rate to economize time, and have its velocity checked immediately before it reaches the head stock to prevent breakage, etc. This variation in the speed of the carriage is effected in the following manner. T is a horizontal shaft carrying the arms U, V, 100 which is connected with an arm W projecting from the belt-shipper X which regulates the position of the belt Y. Z is a lever of the form represented in Figs. 1 and 2 secured firmly beneath the bottom of the carriage. A' is another lever pivoted at i to the bottom of the carriage. One end of this lever is borne up against the lever Z by the spring k as seen in Fig. 1, thus forming a switch which may be opened by pressure in 105 one direction but not in the other.

When the carriage commences to take

out, the belt shipper X and band Y are in the position seen in Figs. 1 and 3 and the carriage takes out with its slow motion. When it arrives near the end of its stretch, the arm V passes the switch formed by the levers Z and A' and as the carriage commences to take in, the arm v is carried over by the lever A', by which means the belt shipper X is moved and the band Y is carried into the position shown in dotted lines in Fig. 3, and the carriage takes in with its fast motion. Before it arrives at the inner end of its stretch, the lever Z upon the carriage strikes the arm U and presses it over again into the position seen in Fig. 1, and the speed of the carriage is thus retarded before it reaches the head stock, the band Y being left in the position required to take the carriage out with its slow motions.

20 I will now describe the manner in which the spindles are driven as the carriage takes out.

The belt shipper B' which governs the belt E is attached to the vibrating shaft C' from which rises the arm l. Beneath the carriage is secured a metallic plate having two inclined edges m, n, by which means the belt is shipped at the proper time as will be hereafter described. The twist pulley D' is secured to the loose pulley H. While the carriage is taking in the belt E runs upon the fast pulley F, and the pulley H no longer driven by the belt is left free to turn as driven by the cord E', the winding on being accomplished by other mechanism which will be hereafter described. When the carriage has reached the forward end of its stretch, the inclined edge m upon its under surface strikes against the pin p upon the belt shipper B' and the belt E is thrown upon the pulley H, and the spindles are thus made to revolve as the carriage takes out. The cord E' after leaving the twist pulley D' passes around the lofer disk of the friction clutch F', thence around the guide pulley q, upon the carriage and over the stationary guide pulley G', thence around the intermediate pulley H' which runs freely upon the spindle t of the friction clutch F', thence around the driving drums I' from which motion is communicated to the spindles r by means of the bands K'. The spindles are thus driven as the carriage takes out, and as the latter reaches the end of its stretch, the incline n upon its under surface strikes against the arm l of the shaft C', and the belt E is shifted onto the pulley F, and the spindles are no longer driven by the twist pulley D'.

60 The yarn is partly stripped and partly backed off as follows: L' is the stripper or under faller wire which is carried by arms M' projecting from the shaft N'. O' is the faller carried by arms P' upon the shaft Q'. It is held up when not in operation by the

spring R', and is connected with the building apparatus in a manner that will now be described. b' is an arm projecting from the shaft Q' to which is hinged the L shaped lever T' which vibrates upon the shaft U' which has its bearing on the carriage. One end of this lever carries a pin c' which rests upon the surface of the former V' as the carriage takes in and passes beneath it as seen in Figs. 2 and 5 as the carriage takes out. The former V' at its outer extremity bends at an acute angle as seen at W' Figs. 2 and 5. d' is a latch or switch pivoted to the "former" at the point e' which is raised by the pin c' upon the lever T' as the carriage reaches the end of its stretch. This latch is seen up in Fig. 5. X' are bearings rising from the floor of the machine to which is hinged the "former" V' by the long rods or bars f' so as to permit V' to rise and fall freely. This up and down motion of the "former" is effected in the following manner: A'' is a metallic plate sliding freely in mortises in the post B''. This plate has two inclines g' upon which rest the rods f' which carry the "former" V'. If now the bar A'' be moved longitudinally in one direction or the other, the "former" will be raised or lowered. This motion of the bar A'' is produced as follows. h' is a nut (Figs. 1 and 2) attached to the outer end of this bar into which works the screw C'' which runs in stationary bearings and carries at its extremity the ratchet wheel D''. i' (Figs. 1, 2, and 4) is a pawl carried by the arm k' which rises from the shaft T. This shaft as already explained vibrates with each in and out motion of the carriage, and through the above connections turns the screw C'' a certain distance each time the carriage takes out, by which means the bar A'' is moved longitudinally, and the inclined planes g' sliding beneath the rods f' raise the former V' as required to build the cop. m' is an arm projecting from the shaft N' which locks with a catch in the arm b' projecting from the shaft Q'. The spring E'' attached to the arm n' projecting from the shaft N' tends constantly to revolve the latter and to raise the under faller wire L', when the arm m' is released from the catch b'. P' is an arm projecting from the shaft N'. To this arm is hung by the adjustable connection q' the lever F'' which is pivoted at the point r'. Through this lever F'' passes the spindle t of the friction clutch F', the upper disk of which slides freely upon this spindle and is connected with the lever F'' by means of collars (Fig. 2) so that

when the lever is raised by the depression of the under faller wire L' and revolution of the shaft N', the clutch is opened and the two disks revolved independently of each other. When however the lever F'' is permitted to yield to the action of its spring 130

G'' the clutch is closed and its two parts revolve together. t' is a pulley attached to the upper half of the clutch and revolving with it. Around this pulley passes the cord H'' which is attached at both ends u' v' to the frame work of the machine. When the friction clutch is closed and the carriage is in motion, the cord H'' drives the pulley t' and also the spindles. This happens when the carriage is taking in, and the winding on is thus effected. At such time it is evident that the driving belt F, must run upon the fast pulley F. The pulleys H and D' as before stated are then permitted to revolve as they are turned by the cord F'. When the carriage takes out, the belt E runs upon the pulley H and the spindles are driven by the cord E'. At such times it is evident that the friction clutch should be opened, and this is effected in the following manner. The under faller wire L' is depressed in the usual manner by the arms I'' which are suitably connected thereto and pass between the projections K'' from the front of the roller beam, and the shaft N' is thus revolved until the arm m' passes beneath the catch b' and through the connections p' q' F'' the clutch is kept open. The pin c' upon the lever T' having passed over the end of the former V' the shaft Q' is revolved by the spring R' and the catch b' holds the arm m' fast. When the carriage reaches the end of its stretch, the pin c' comes in contact with the inclined W' up which it slides past the latch d' by which means the shaft Q' is revolved and the arm m' escapes from the catch b'. As soon as this takes place, the spring E'' throws up the stripper L' at the same instant the lever F'' descends, the friction clutch is closed and the spindles through the cord H'' and pulley t' receive a slight backward motion which backs off the balance of the yarn, the driving belt E having been previously shipped onto the pulley F. The winding on may be accomplished by the motion of the carriage in a manner analogous to that above described, the extra cord H'' being dispensed with, and the driving cord E' being caused to perform the spinning as described when the carriage takes out and to perform the winding on as it takes in. Fig. 7 is a diagram for the purpose of illustrating this method of winding on. 1 is the driving pulley or twist pulley upon the head stock. 2 is a loose or carrying pulley upon the same shaft. 3, 4, and 5 are loose pulleys upon a common shaft upon the carriage. 7 and 8 are loose pulleys upon a stud at the lower end of the machine. 6 is a pulley attached to the drum which drives the spindles. The pulley 3 is encircled by a friction band brake which is operated by the faller and under faller in manner precisely similar to that in which the friction clutch is op-

erated. As the carriage takes out the twist pulley 1 drives the spindles and the spinning is performed, all the other pulleys except 6 operating only as carrying pulleys. When the carriage takes in, the pulley 3 is clamped fast and prevented from turning the driving belt at the same instant being so shifted that the pulley 1 becomes a loose or carrying pulley. The cord g being clamped to the carriage is driven by it as it takes in, and the winding on is thus accomplished by the motion of the carriage.

Some contrivance becomes necessary to give an equable surface motion to the cop driving, the winding on process, and this is accomplished in the following manner. The yarns on the way from the delivering roller pass beneath the faller wire O' and over the under faller L'. If now the tension of the yarns becomes considerable they depress the under faller and by means of the connection between it and the friction clutch, the latter is opened or allowed to slip slightly until the under faller again yields to the action of the springs E'' and G'' and thus the winding on is effected under an uniform tension, whatever may be the size of the cop.

Other parts of the machinery not immediately connected with my improvements it is deemed unnecessary to describe.

The extreme simplicity of the mechanism above described results from the use of the cone pulleys for the purpose of imparting the varying motion to the carriage. The operation of these cones has been found to be most perfect, particularly where the lower cone has been hung upon a weighted or spring lever.

Operation: Commencing with the carriage as it begins to take out, the belt E running upon the pulley H and the belt Y being in the position seen in Fig. 1, the carriage runs out with a slow motion and the spindles are driven by the cord E' upon the twist pulley D' in the manner described, the friction clutch F' having been opened by the depression of the counter faller wire L', which state of things is maintained by the arm l' which catches over the arm m' as already explained and as seen in Fig. 2. The pin c' upon the lever T' having passed over the end of the "former" V', the faller Q is held up out of the way of the yarns as in Fig. 2, by the spring R' assisted by the weight of the lever T'. As the carriage nears the end of its stretch the incline n' strikes the arm l and shifts the belt E to the pulley F and the spindles are no longer driven by the twist pulley D' which as before stated runs together with the pulley H loosely upon the shaft G. The next instant, by the rising of the pin c' up the inclined plane W', the arm m' is loosed from the catch l' and the under faller L' is thrown up; the friction clutch

F' closing just before the carriage has completed its outward motion, the spindles make a few retrograde revolutions and the balance of the yarn is backed off. The pin c' has 5 now ascended the inclined plane W' and passed the latch d', and in so doing has depressed the faller wire o' which is now in position to commence the building of the cop. The arm V upon the shaft T having 10 during the last moments of the outward traverse passed between the levers Z and A' raising the point of the latter against its spring k, is now in position to be operated upon by the lever A' for the purpose of 15 shifting the belt Y upon the cone pulleys into the position seen in dotted lines in Fig. 3, and also, by means of the pawl i'' and ratchet wheel D'', of giving motion to the plate A'' which raises at each traverse the 20 former and thus guides the building of the cop. The carriage now commences to take in with its fast motion, the clutch F' remaining closed the spindles are driven by the cord H'' as already explained, and should 25 the yarn, as the cop increases in size, become too tight, the under faller is depressed which opens the clutch and permits the disks to slip upon each other, and thus retard the motion of the spindles as required. The pin 30 c' upon the lever T' rests upon the surface of the "former" V' as the carriage takes in, by which means the motion of the faller is governed and the cop is formed.

As it would not be safe to permit the carriage to arrive under the speed with which it takes in, before it reaches the head stock 35 the lever Z strikes the arm U and shifts the belt Y into the position seen in Fig. 1, and the motion of the carriage is eased off as it 40 comes in. The under faller is then depressed and the friction clutch opened by the passage of the arms I'' beneath the projections K'', the arm m' passing beneath the catch l' which has the instant before been depressed 45 by the dropping of the pin c' over the end of the "former" V'. The incline m now strikes the pin p upon the belt shipper B' and shifts the belt E onto the pulley H, and

the spinning again commences as the carriage takes out.

50

It will be perceived that the rotary motions of my mule, with the exception of the backing off of the yarn, are all continuous and I am thereby enabled to run my machine at a speed far greater than can be 55 attained where heavy cogged gearing is to be constantly stopped and reversed, while the original cost of construction is greatly reduced.

What I claim as my invention and desire 60 to secure by Letters Patent, is—

1. Driving the carriage in and out by the continuous motion of the cone pulleys in combination with some method of automatically shifting the belt, for the purpose of 65 adapting the speed of the carriage to the requirements of the different parts of its traverse, by which means I am enabled to dispense with the complicated mechanism heretofore adopted for the attainment of the 70 same end.

2. I claim the pulleys F and H upon the shaft G arranged and operating substantially as described, by which a continuous motion in one direction is given to the shaft 75 G for the purpose of driving the carriage, and an intermittent motion to the twist pulley D', when the winding on is accomplished by mechanism independent of the motion of the twist pulley.

80

3. I claim the friction pulley F' or its equivalent constructed and operating substantially as described, in combination with an efficient method of regulating the speed of the spindles by the tension of the yarns 85 in the manner set forth, by which means I dispense with the complicated machinery heretofore made use of to regulate the winding on, and am enabled to run my machine at a speed far exceeding that which can be 90 attained where the motions of heavy cogged gearing are to be constantly reversed.

GEORGE WRIGHT.
